UNITED STATES PATENT OFFICE.

WILLIAM H. RANAGAN, OF VINELAND, NEW JERSEY.

MACHINE FOR GRINDING BOTTLES AND STOPPERS.

Application filed November 3, 1923. Serial No. 672,645.

To all whom it may concern:

Be it known that I, WILLIAM H. RANAGAN, a citizen of the United States, and a resident of Vineland, county of Cumberland, State 5 of New Jersey, have invented certain new and useful Improvements in Machines for Grinding Bottles and Stoppers, of which the following is a specification.

This invention relates to a machine for 10 grinding necks and stoppers for bottles and, more particularly, to a machine whereby when the bottles or stoppers are placed in position in the machine they are automatically carried through a definite grinding 15 operation.

Bottles and stoppers of the type to which the present invention are to be applied are commonly blown or formed with smooth necks and stopper surfaces, respectively, of approximately the proper size and are provided with the desired roughened surface by grinding with emery dust or other suitable abrasive. This is done in a lathe, the bottles or stoppers being placed individually 25 in the lathe one at a time and requiring the attention of an operator during the grinding. The grinding of the bottles or stoppers in this manner has heretofore accordingly consumed considerable time and labor.

30 An object of my invention is to provide a machine in which a number of bottles or stoppers may be ground simultaneously.

Another object of the invention is to provide a machine in which bottles and stoppers 35 need only be inserted and removed at the proper positions and are then automatically ground without further attention by the operator.

40 Other objects and features of the invention are the provision of means for automatically feeding emery dust or abrasive to the grinding surfaces, means for controlling the rate of feeding the abrasive and of a grinding means that may be readily adjusted for grinding bottles and stoppers of 45 various sizes and dimensions.

With these and other objects in view the invention comprises the apparatus described and set forth in the following specification and claims.

50 The various features of the invention are illustrated in the accompanying drawings in which:

55 Fig. 1 is a side elevation of a grinding machine embodying a preferred form of the invention.

Fig. 2 is a vertical sectional view of the machine taken on line 2—2 of Fig. 1.

Fig. 3 is a plan view of the machine taken on line 3—3 of Fig. 2.

Fig. 4 is a horizontal sectional view of the machine taken on line 4—4 of Fig. 2.

Fig. 5 is a side elevation of a carriage showing the arrangement for grinding bottle necks.

Fig. 6 is an elevation of the carriage taken on line 6—6 of Fig. 5.

Fig. 7 is a side elevation of the carriage arranged for grinding bottle stoppers.

Fig. 8 is a dis-assembled perspective view 70 of the stopper and its holding and grinding means.

In my present invention the bottles are placed individually on individual carriers and carried through a circuit in which they 75 are brought into relation to a rotating grinding element. Emery dust or other suitable powdered abrasive is fed down between the rotating grinding element and the neck of the bottle, or the surface of the stopper in 80 case a stopper is being ground, and the rotating element is slightly reciprocated axially at intervals during the grinding to permit the abrasive to reach and spread uniformly over the surface to be ground. The 85 bottles or stoppers are carried through the circuit in this manner and are then displaced axially out of operative relation to the grinding tools and replaced by new bottles or stoppers to be ground. The bottles or 90 stoppers are resiliently held against the grinding tool and the positions of the carriages carrying the bottles or stoppers may be varied relatively to the grinding element to enable objects of various sizes and 95 dimensions to be ground.

Referring more particularly to the accompanying drawings, the bottles 10 to be ground are placed on individual carriers 12 mounted in spaced relation on a rotatable 100 spider 14. The carriages 12 are slidably supported on the spider 14 by means of lugs 18 mounted on upright backs 20 on the carriages and slidable in vertical grooves 22 in upright standards 24 at the outer ends of 105 the spider 14. The carriages 12 are urged upwardly by means of a weight 26 or equivalent device suspended on a chain 28 which is attached at its other end to the carriage 12 and is passed over a pulley 30 mounted 110 on a bracket 32 at the upper end of the upright standards 24. The weights 26 are

kept in proper position by means of guiding uprights 31 at either side of each weight.

The spider is mounted on and fixed by means of a set screw 33 to a rotatable sleeve 34 encircling and rotatable on a shaft 36 and resting on a supporting base 40 of the machine. The spider is rotated by means of a cog wheel 42 fixed on the sleeve 34 by means of a set screw 43 and driven by means 10 of a chain 44 from any suitable source of power.

Above each of the carriages 12 is a rotating grinding tool 46 mounted on the lower end of a vertical spindle 48 which is mounted in a vertical bearing 50 carried on the outer end of a radial vane 52 extending outwardly from the upper portion of the sleeve 34. The spindle 48 is rigidly attached to and supported from, a gear wheel 54 resting on the upper face of the bearing 50 and is guarded from upward displacement by means of a socket 56 into which the lower end of the spindle 48 is threaded or otherwise secured and which rests against the lower face of the bearing 50. An extension shaft 58 is inserted into the lower face of the socket 56 and carries at its lower end the grinding tool 46 which projects into the neck of the bottle 10 immediately beneath it as the carriage 12 is forced to its uppermost position by means of the weight 26.

The gears 54, and their spindles 48 and grinding tools 46 are rotated in unison by means of a central gear wheel 60 which meshes with each of the gears 54. The gear wheel 60 is rigidly supported on the upper end portion of the shaft 36 by means of a hub 62 on the wheel and a set screw 64 mounted on the hub and engaging the shaft.

The shaft 36 is rotated independently of, and relative to, the sleeve 34 and its associated parts by means of a cog wheel 66 rigidly mounted on the upper portion of the shaft and driven from any suitable source of power by means of a chain 68. The shaft 36 is supported at its lower end in a socket or recessed boss 70 on the base 40 of the machine and is supported at its upper end in a bearing 72 carried on a supporting arm 74 extending upwardly from the base 40.

In the operation of the apparatus, the spider 14 is rotated slowly and the wheel 60 is rotated at a different rate of speed so that the spindles 48 and grinding tools 46 are rapidly rotated. At the same time a supply of abrasive is fed downwardly about the grinding tool and spreads between the grinding tool and the neck of the bottle or other surface to be ground. For this purpose a supply of the abrasive in water or other suitable fluid medium is carried in an annular trough 76 having openings 78 in which the rotating elements of the grinding tools are positioned. The abrasive is

fed to the grinding tools in a regulated stream, preferably by making the openings 78 of slightly larger diameter than the diameters of the rotating elements to form an annular space through which the abrasive may fall to the grinding tools. To enable the supply of abrasive to be regulated, a pair of semi-circular gates 80 see Figure 3 are pivoted at 82 about, and immediately beneath, the openings so that the space for 75 the passage of the abrasive to pass may be enlarged or decreased.

To insure the proper distribution and penetration of the abrasive between the grinding tools and the surfaces to be ground, 80 the bottles and grinding tools are given a slight relative movement longitudinally, thereby enlarging the space therebetween and permitting the abrasive to flow freely to the grinding surface. For this purpose, the carriages are each depressed slightly during each revolution of the gear wheel 60 by means of a cam 84 mounted on the under side of the gear 60 in position to depress a follower rod 86 for each carriage. The follower rods 86 are slidably mounted in individual guides 88 on the wings 52 and are connected at their lower ends through extensible links 90 to levers 92, pivoted at one end on brackets or lugs 94 on the circumference of the sleeve 34 and, at their other ends, bearing on the upper edges of the upright faces 20 of the carriages 12. Accordingly, as the rods 86 are depressed by the cam 84, the levers 92 and the carriages 12 are accordingly slightly depressed, the cam being so proportioned that this depression is just sufficient to permit the abrasive to flow to the grinding surface.

After passing through the grinding cycle, each bottle is removed and replaced by a new bottle to be ground. For this purpose, the carriage 12 is depressed at one locality in each rotation by means of a cam 96, supported on standards 98, on the base 40, beneath the spider 14 and carriages 12 in such position as to engage the upper face of a hook 100 depending from the underside of the carriage 12. When the hook 100 passes under the cam the carriage is depressed until the neck of the bottle is below and free from the grinding tool 46, and is held in depressed position for a sufficient time to permit the bottle to be removed and replaced by a new one. The hook 100 then passes from beneath the cam and the carriage is released and drawn upwardly by the weight 26.

The bottle is held in position on the carriages 12 by means of upright fingers 102 and 104 on either side of the carriage, by the upright back 20 and by an engaging lever 106 on the front part of the carriage, which may be operated to press the bottle against the back 20 or to release the bottle 130

so that it may be withdrawn. For this purpose the lever 106 is pivoted between a pair of supports 108 on the carriage and has an arm 110 for engaging the side of the bottle 5 and an arm 112 extending outwardly by which the lever may be operated. The back 20, fingers 102 and 104 and the arm 110 of lever 106 are each covered with a strip of rubber or equivalent cushioning material at 10 the places where they contact with the bottle.

The machine may also be arranged to 15 grind the surfaces of stoppers. For this operation the stopper 114 is mounted in inverted position on a holder 116 having a slot or socket 117 into which the top of the stopper may be inserted. The holder 116 may be mounted on the carriage in the same manner as a bottle. The bottle grinding tool is 20 replaced by a tool 118 that fits over the stopper surface, the tools 46 and 118 for a single set of bottles and stoppers being so shaped that they fit each other. The tool 118 is also provided with an opening 120 in 25 its side walls through which the abrasive may flow to the stopper surface.

The machine may be adjusted for operation 30 on bottles and stoppers of various dimensions and heights. In adjusting the machine for bottles of different diameters or different cross sectional dimensions, the carriages 12 are moved inwardly towards or outwardly from, the shaft 36 until the back 20 is at a distance from the axis of rotation 35 of the grinding tool equal to the radius of the bottle. For this purpose, the arms of the spider 14 are provided with radial slots 122 and the carriages are mounted on the spiders by means of rearwardly extending 40 horizontal brackets 124 resting on the arms of the spider and slidably mounted thereon and secured thereto by means of a bolt 126 extending downwardly through the slot 122 and fastened by means of a nut 128. The carriages are rigidly kept in proper position 45 on the spider arms by means of lugs 130 depending downwardly from the brackets 124 into the slots 122.

When the carriages are thus adjusted the 50 fingers 102 and 104 and the brackets 108 and levers 106 are also adjusted to center the bottles or stoppers under the grinding tools. To this end each carriage is provided with a sidewise ledge 132 and 134 at either side 55 of the carriage on which the fingers are mounted by means of sidewise projecting bases 136 and 138 and each ledge is provided with a slot 140 through which passes a bolt 142 depending from the projections 60 126 and 138 for adjustably mounting the fingers on the ledges. In a similar manner the lever bracket 108 is slidably and adjustably mounted on a forwardly projecting ledge 144 on the carriage 12 by means of a bolt 146.

The apparatus may also be adjusted to 70 operate on bottles of various heights by adjusting the altitude or vertical position of the spider 14 and the carriages and mechanism associated therewith. The spider and its associated carriages may be raised or lowered by loosening the set screws 33 and 43 and adjusting the spider 14 and sprocket wheel 42 to bring the spider and carriages 75 12 to the proper height.

The height of the cam 96 is also adjusted to 80 correspond with the height of the spider and carriages by making the standards 98 extensible. For this purpose the standards are made of a lower upright 148 mounted directly on the base 40 and an upper member 150 to which the cam 96 is attached and which is provided with a guiding flange or lug 152 and a clamping bolt 154 slidable in 85 vertical slots 156 in the lower upright 148.

As the spider 14 is lowered, the levers 92 and the rod 86 are also lowered. To bring the rod 86 into proper position relative to the cam 84 the link 90 is provided with a slot 158 through which pass bolts 160 attached to the lower end portion of the rods 86 in such manner that they may be loosened to adjust the relative position of the link and rod and then tightened to hold them in 90 adjusted position and to transmit downward thrusts from the cam 84 to the levers 92.

In the operation of the machine the spiders 14 are rotated at a speed that causes the carriages to be held in their lowered position by the cam 96 for just sufficient time to 100 permit a finished or ground bottle or stopper to be removed and a new one to be inserted in the carriage and tightened by means of the lever 106. The capacity of the machine is thus limited only by the time required to replace bottles or stoppers. The gear 60 is rotated at such a speed relative to the gear 42 and carriages 12 as to give the grinding tools 46 the number of revolutions required 105 to grind a bottle or stopper in a single revolution or cycle. The slight depression of the carriages 12 and bottles 10 at definite intervals by means of the cam 84, rods 86 and levers 92 in connection with the proper adjustment of the feed gates 80 for the abrasive, insures a proper supply and distribution of the abrasive over the surface to be ground.

As changes of construction could be made 110 within the scope of my invention, it is intended that all matters contained in the above description or shown in the accompanying drawings, be interpreted as illustrative and not in a limiting sense.

Having described the invention, what I 115 claim and desire to secure by Letters Patent is:

1. A machine of the type described which 120 comprises, a series of carriages for holding bottles or stoppers, means for carrying said 125

carriages through a definite circuit, means for carrying grinding tools through said circuit each in operative relation to an object on a carriage, means for rotating said tools relative to objects on said carriage, means for feeding abrasive to said grinding tools, means for controlling the feed of said abrasive, and means for causing a slight relative axial displacement between each of said carriages and its tool at intervals during grinding to enable said abrasive to penetrate between said tool and the surface being ground.

2. A machine of the type described which comprises, a series of carriages each holding a bottle or the like, means for carrying said carriages through a definite circuit, means for carrying a grinding tool for each carriage through said circuit and rotating it in operative relation to the object on said carriage, means for resiliently pressing each said carriage towards said tool, means for feeding abrasive to said tool, and means for pressing said carriage slightly away from said tool at intervals.

3. A machine of the type described which comprises, a series of carriages for bottles or the like, means for carrying said carriages through a definite operative circuit, means for rotating and carrying a grinding tool for each carriage through said operative circuit relative to said carriage, means for yieldingly holding said carriages to operative position with said tools, means for feeding abrasive to said tools, means for slightly displacing said carriages against the action of said yielding means at intervals during grinding to permit penetration of abrasive between said tool and the surface to be ground, and means for displacing each said carriage to permit removal and replacement of objects to be ground during a portion of said circuit.

4. A machine of the type described, which comprises a series of carriages for bottles or the like, means for carrying said carriages through a definite operative circuit, means for rotating and carrying a grinding tool shaft for each carriage through said operative circuit with said carriage, means for yieldingly holding said carriages to an operative position relative to said tool device, means for feeding the abrasive to the tools, means for slightly displacing said carriages against the action of said yielding means at intervals during grinding to permit penetration of abrasive between the tool and the surface to be ground, and means for displacing each said carriage to permit removal and replacement of objects to be ground

during its progress of said circuit, each said carriage having means for interchangeably holding a bottle or a stopper and interchangeable internal and external grinding surface tools for each tool shaft.

5. A machine of the type described which comprises, a rotatable member, carriages mounted on said member, means for carrying and rotating tools one tool above each carriage, and an abrasive carrying pan having openings through which said tools project and providing spaces through which abrasive may flow to said tools.

6. A machine of the type described which comprises, a rotatable member, carriages mounted on said member to support objects to be operated upon, means for carrying and rotating tools, one tool above each carriage, an abrasive carrying pan having openings through which said tools project, and providing a space around each tool through which abrasive may flow to said objects, and means for controlling the flow of abrasive through said openings.

7. A machine of the type described which comprises, a rotating member, carriages mounted circularly on said member, grinding tools mounted one above each carriage, a main driving gear rotatable relative to said carrier for rotating said tools on their axes, means for yieldingly pressing said carriages towards said tools, a cam on said main gear, levers pivoted on said carrier and projecting over said carriages, rods attached to said levers and slidably mounted on said carrier to be depressed by said cam and to depress said levers and carriages slightly at intervals, means permitting an adjustment of said member relative to said tools and means permitting lengthening or shortening said rods to correspond with the position of said member.

8. A machine of the type described which comprises, a vertical shaft, a member rotatably mounted on said shaft, carriages mounted on said member, tools mounted, one above each carriage and rotating with said member, means for resiliently pressing said carriages individually upwards towards said tools, individual gears for rotating said tools on their axes, a central gear for rotating said gears simultaneously, individual levers mounted to depress said carriages, a cam on said central gear and means for depressing said levers slightly from said cam, and a cam adapted to depress said individual carriages at a part of their path of travel to permit the positioning or removal of an article to be operated upon.

WILLIAM H. RANAGAN.
